UNITED STATES PATENT OFFICE.

HENRY J. SMALL, OF SACRAMENTO, CALIFORNIA.

NUMBER-DISPLAYING DEVICE FOR CABOOSE-CARS.

SPECIFICATION forming part of Letters Patent No. 621,862, dated March 28, 1899.

Application filed July 18, 1898. Serial No. 686,284. (No model.)

To all whom it may concern:

Be it known that I, HENRY J. SMALL, of Sacramento, in the county of Sacramento and State of California, have invented a certain 5 new and useful Improvement in Number-Displaying Devices for Caboose-Cars, of which improvement the following is a specification.

The object of my invention is to provide simple and effective means for clearly displaying 10 on either end of the cupola of a caboose-car an indication which may be easily read, either by night or day, of the number of the train if the train be a regular one or the number of the locomotive in case the train is an extra. 15 The improvement claimed is hereinafter fully set forth.

In the accompanying drawings, Figure 1 is a vertical transverse section through the cupola of a caboose-car, showing in elevation 20 my improvement applied on one end thereof; Fig. 2, a vertical central section through the end of the caboose, and Fig. 3 a horizontal section.

In the practice of my invention either or 25 each of the ends of the cupola 1 of a caboose-car is provided with an outer window-sash 2 of suitable size and glazed with a plate of plain glass 3. On the inside of the sash 2 and near thereto an inner sash 4, having a 30 number of spaces or openings side by side and separated by narrow vertical bars 5, (six of said openings ordinarily sufficing for the requirements of trunk-line service,) is hinged to the sill 6 of the window-frame. The inner 35 sash 4 is held in place by a button 7 at the top and is provided with suitable upper and lower grooves of sheet metal for the reception of marker-plates 8, each bearing a number, letter, or other designation and translucent 40 backing-slides 9, which are preferably of ground plate-glass and are usually colored green. The marker-plates may be made of sheet brass, tin, paper, or other suitable material painted black, and the letter, figure, 45 or other designation of each is cut out in the manner of a stencil. The marker-plates are set on the outside of the backing-slides, and their designations are plainly shown by the exposed portions of the backing-slides, which 50 are prominently marked by the surrounding black surfaces of the marker-plates and are thus easily seen in the daytime. The marker-

plates and backing-slides which are not in use are stored in a case 10, provided with suitable partitions and fixed to the end of the 55 cupola below the window-sill.

When running at night, the indications of the marker-plates and slides are made visible by any suitable illuminating means, as a lamp or lamps 11, inclosed in a reflector-case 60 12, of sheet metal, the interior of which may be painted white or polished and which is located behind and in line horizontally with the inner sash 4. The reflector-case is hinged at one end to the cupola by a pin 13 and is 65 held in position by a pin 14 at the opposite end, so that it may be swung back when required to trim or light the lamp or lamps. The rays of light projected through the glass backing-slides give a clear indication at night. 70

A sufficient number of marker-plates is provided to give the numerals of the different trains and locomotives in service, and marker-plates are also provided stenciled with an "X" and dash and with the ordinals of train-sections, as "1st," "2nd," &c. If the train consists of more than one section, the ordinals of such section will precede the train-number, or if the train be an extra the number of the locomotive will be given and preceded by the 80 letter "X" and a dash—as, for example, "X—2019."

It will be seen that the display of any desired indication of train or locomotive number may be plainly given and be readily and 85 promptly changed whenever desired, and, further, that the appliance is conveniently applicable at comparatively slight expense to caboose-cars of any of the ordinary styles now in use. 90

I claim as my invention and desire to secure by Letters Patent—

1. In a number-displaying device for caboose-cars, the combination of an outer plain glazed sash in the cupola of the caboose, a 95 second sash hinged to the interior of the cupola adjacent to the outer sash and having a plurality of spaces side by side, backing-slides adapted to fit in the spaces of the inner sash, and marker-plates, each having a cut-out or stenciled designation and adapted to fit in a space of the inner sash on the outside of a backing-slide. 100

2. In a number-displaying device for ca-

boose-cars, the combination of an outer plain glazed sash in the cupola of the caboose, a second sash hinged to the interior of the cupola adjacent to the outer sash and having a plurality of spaces side by side, translucent backing-slides adapted to fit in the spaces of the inner sash, marker-plates, each having a cut-out or stenciled designation and adapted to fit in a space of the inner sash on the outer side of a backing-slide, and an illuminating device supported behind or at the inner side of the inner sash.

3. In a number-displaying device for caboose-cars, the combination of an outer plain glazed sash connected to one end of the cu-

pola of a caboose-car, a second sash hinged to the interior of the cupola adjacent to the outer sash and having a plurality of spaces side by side, translucent backing-slides adapted to fit in the spaces of the inner sash, marker-plates, each having a cut-out or stenciled designation and adapted to fit in a space of the inner sash on the outside of a backing-plate, a reflector-case pivoted to the cupola behind or at the inner side of the inner sash, and a lamp, supported in the reflector-case.

HENRY J. SMALL.
